FLEXIBLE CONTAINER FOR HAND PISTOLS

Harvey Brent Mason, 142 Loma Vista, Covina, Calif.

Filed Apr. 30, 1964, Ser. No. 79,743

Term of patent 14 years

(Cl. D58—2)

FIG. 1 is a top plan view of a flexible container for hand pistols showing my new design;

FIG. 2 is a side elevational view thereof taken from the left of FIG. 1;

FIG. 3 is a cross-section taken at line 3—3 of FIG. 1.

I claim:

The ornamental design for a flexible container for hand pistols, as shown.
